UNITED STATES PATENT OFFICE.

WALTER KIESER, OF CHARLOTTENBURG, GERMANY, ASSIGNOR, BY MESNE ASSIGNMENTS, TO ALLGEMEINE ELEKTRICITATS GESELLSCHAFT, OF BERLIN, GERMANY, A CORPORATION OF GERMANY.

GOVERNING MECHANISM FOR TURBINES.

Application filed November 13, 1923. Serial No. 674,523.

To all whom it may concern:

Be it known that I, WALTER KIESER, a citizen of Switzerland, residing at Charlottenburg, Germany, have invented certain 5 new and useful Improvements in Governing Mechanisms for Turbines, of which the following is a specification.

The present invention relates to governing mechanisms for turbine installations in 10 which a pair of turbines is arranged to drive a common load, such as an electric generator for example, and in addition to independently supply steam for heating and cooking purposes. In such installations the 15 requirements on the governing mechanism are unusually exacting as will be appreciated from the fact that the load on the generator may vary as well as the amounts of steam extracted from the turbines and that these 20 variations may take place simultaneously and in the same or different directions.

The object of my invention is to provide a simple, reliable governing mechanism for installations of the general character above 25 referred to. For a consideration of what I believe to be novel and my invention, attention is directed to the accompanying description and the claims appended thereto.

In the attached drawing is illustrated 30 more or less diagrammatically one of the embodiments of my invention.

1 indicates a multistage turbine of suitable construction arranged to operate as a condensing and extraction unit. The extraction 35 pressure may be approximately that of the atmosphere or above it as desired. For simplicity it will be referred to as the main turbine. 2 indicates the steam supply pipe, 3 the admission valve therefor, 4 the extraction conduit, 5 the overflow valve regulating the supply of steam from the extraction stage to the lower pressure stages, and 6 the exhaust conduit which may be, and 40 usually is connected to a condenser.

45 7 indicates what is commonly termed a "back pressure" turbine, meaning thereby one which exhausts at a pressure somewhat above atmosphere, the exhaust steam being utilized at some distance point for heating, 50 cooking or other purposes. For simplicity it will be referred to as the auxiliary or secondary turbine. 8 indicates the steam supply pipe, 9 the admission valve therefor and 10 the conduit conveying the exhaust to

the point of consumption. Both turbines 55 have their rotors mounted on the same shaft 11 and through it drive the rotor of the electric generator 12. The generator is designed to be driven at constant or approximately constant speed as is usually the case. 60

The regulating valves 3, 5 and 9 are operated by fluid motors of ordinary construction, each comprising a cylinder 13 and piston 14, the latter being connected to the valve to be operated. The movements of 65 each piston are controlled by a pilot valve 15 of usual construction. Each pilot valve stem is also connected to the piston rod of its motor as by a lever 15^a which forms a follow-up device to prevent overtravel of the 70 motor.

The mechanism for controlling the actions of the main regulating valves will now be described. 16 indicates a centrifugal speed governor driven by any suitable means from 75 the main shaft 11 whereby its effective action varies with changes of speed of the shaft. The movable collar of the governor is pivotally attached to a lever 17 through the medium of a fulcrum or pivot 28. The 80 left-hand end of this lever is provided with a pivot 29 which is connected by a system of links and levers to the pilot valves of the motors which actuate the controlling valves of the main turbine 1. To the lever 18 of 85 said system is connected a pressure responsive device 19, such for example, as a piston and cylinder in which the outward movement of the piston is opposed by a coiled compression spring. Fluid under the pressure corresponding to the extraction pressure of the main turbine is admitted to the upper side of the piston of the regulator by 90 the conduit 20. As the extraction pressure varies, the regulator exerts its influence 95 through lever 18 on the admission valve 3 and overflow valve 5 opening one and closing the other as may be required to preserve the proper speed of the shaft 11. It is to be noted that the load variations of the 100 generator between certain rather wide limits are taken care of by varying the amount of steam flowing through the main turbine, and that when the load is decreased below the lower of said limits further governing 105 is accomplished by varying the amount of steam flowing through the auxiliary or secondary turbine.

The right-hand end of governor lever 17 is pivotally attached to the rod 21 which forms a part of the governing mechanism of the back pressure or secondary turbine. 5 22 indicates a pressure regulator of the same character as regulator 19 and its action is responsive to the extraction or exhaust pressure in the conduit 10.

In order that a single speed governor may 10 control both turbines, an elastic coupling 23 is provided in one of the systems of links and levers. As illustrated it is associated with the secondary turbine 7 and is located in the rod 21 between the pressure regulator 15 and the mechanism controlled thereby. It comprises a member 24 connected to the movable part or piston of the regulator 22, and abutment 25 on the rod 21 and a coiled compression spring 26 between the member 20 and abutment. Under normal conditions the tension of the spring is such that it and its associated parts move with the rod 21 and piston of the regulator 22 as a unit, but under other conditions the spring 26 yields 25 to permit the speed governor to control the valve 9 as will appear later.

The operation of the governing mechanism is as follows: For changes in load on the generator the speed governor 16 30 opens or closes the valves 3 and 5 as required to maintain the desired speed, the lever 17 moving about its pivoted connection with the rod 21. A variation in the amount of steam taken from the extraction conduit 4 causes the pressure regulator 19 to modify 35 the action of the governor on the valves. This is done through the lever 18 turning on the pivot 27 in a manner to increase the opening of one valve and decrease that of the other. The pressure regulator 22 is 40 sensitive to variations in the amount of steam flowing through the secondary turbine and controls the valve 9. Under normal conditions the regulator 22 in causing a decrease of 45 steam admitted to the secondary turbine by the valve 9, also acts on the governor lever 17 turning it on pivot 28 in such a manner as to open the valves 3 and 5 so that the speed of the set as a whole will be maintained. 50 When the load decreases below that requiring the two turbines to drive it, the governor first closes the valves 3 and 5 and then begins to close the valve 9, this being 55 permitted by the elastic coupling in the rod 21. In other words the governor through the lever 17 and pivot 29 exerts sufficient pressure to compress the spring 26 in the elastic coupling 23 thereby permitting the rod 21 to move in a direction to cause a 60 decrease of the opening of valve 9. From the foregoing it will be seen that the pressure regulator 22 in addition to directly controlling the secondary turbine also performs the function of dividing the load between said turbines. Also that under certain conditions 65

the speed governor assumes control of the secondary turbine to the exclusion of the regulator.

In accordance with the provisions of the patent statutes, I have described the principle of operation of my invention, together with the apparatus which I now consider to represent the best embodiment thereof; but I desire to have it understood that the apparatus shown is only illustrative, and 70 that the invention may be carried out by other means.

What I claim as new and desire to secure by Letters Patent of the United States, is,—

1. In combination, a main turbine, an auxiliary turbine operating on the extraction plan, said turbines being arranged to drive a common load, admission valves for the turbines, a speed governor which successively controls said admission valves, and a regulator responsive to a condition of the fluid extracted from the auxiliary turbine which normally controls its admission valve, and which also modifies the action of the governor on the admission valve of the main turbine in such manner as to cause said valve to move in the opposite sense to the valve of the auxiliary turbine. 80

2. In combination, main and auxiliary turbines both operating on the extraction plan and arranged to drive a common load, admission valves for the turbines, a speed governor which normally controls the admission valve of the main turbine, a regulator sensitive to the pressure of the fluid extracted from the auxiliary turbine which normally controls its admission valve, a regulator sensitive to the extraction pressure of the main turbine, said regulators acting on the speed governor in such manner as to cause it to vary the admission of fluid to the main turbine between predetermined load variations and to cause it to assume control of the admission of fluid to the auxiliary turbine for loads below said limit. 90

3. In combination, a main turbine, an auxiliary turbine operating on the extraction plan, said turbines driving a common load, admission valves for the turbines, a regulator responsive to the extraction pressure of the auxiliary turbine, mechanism controlled by the regulator which includes an elastic coupling for normally actuating the admission valve of the auxiliary turbine, a speed governor which normally controls the operation of the admission valve of the main turbine, and means connecting the governor to said mechanism in such manner that under conditions of decreasing load the governor first shuts off motive fluid to the main turbine and thereafter acts in opposition to the pressure regulator to decrease the admission of fluid to the auxiliary turbine. 100

4. In combination, a main elastic fluid turbine and an auxiliary back pressure tur- 110

bine connected with a common load, elastic fluid admission valves for said turbines, a pressure regulator responsive to the extraction pressure of the auxiliary turbine operatively connected with said admission valves to move and control the same, a rod in the connection between the pressure regulator and the admission valve of the auxiliary prime mover, a lever in the connection 10 between the pressure regulator and the admission valve of the main turbine, said lever being pivotally connected at one end with the rod and having a fulcrum between its ends whereby said valve is moved by the 15 pressure regulator in an opposite sense to that of the auxiliary turbine through the intermediary of said lever, and a speed governor operatively connected with the fulcrum of said lever.

20 5. In combination, a main elastic fluid turbine and an auxiliary back pressure turbine connected with a common load, elastic fluid admission valves for said turbines, a pressure regulator responsive to the extraction 25 pressure of the auxiliary turbine, a rod operatively connected with the admission valve of the auxiliary turbine and with the pressure regulator, an elastic coupling in said rod, a speed governor, a governor lever 30 therefor pivotally connected with the rod at a point between the elastic coupling and the point of connection with the admission valve of the auxiliary turbine, and means operatively connecting the lever with the admission valve of the main turbine.

35 6. In combination, a main elastic fluid turbine, an auxiliary back pressure turbine, said turbines being connected with a common load, admission valve mechanisms for said 40 turbines, a speed governor operatively connected with the valve mechanism of the main turbine to control the same, a pressure responsive device operated by the back pressure of the auxiliary turbine operatively 45 connected with the admission valve thereof to control said valve, means providing an operative connection between the speed governor and the pressure regulator whereby through said connection the latter modi- 50 fies the action of the speed governor on the

admission valve of the main turbine, and an elastic coupling means in said connection which permits the speed governor to move and control the admission valve of the auxiliary turbine under certain operating conditions.

7. In combination, a main and an auxiliary elastic fluid turbine, both being of the extraction type and being arranged to drive a common load, elastic fluid admission 60 valves for the turbines, a pressure regulator responsive to the extraction pressure of the auxiliary turbine operatively connected with the admission valve thereof, a speed governor, a governor lever therefor operatively connected with the pressure regulator, an overflow valve for the main turbine, a pressure regulator responsive to the extraction pressure of the main turbine, a lever connected therewith, a fulcrum for the 65 lever connected with the governor lever, and means operatively connecting the overflow and admission valves of the main turbine with said lever in spaced relation to and on opposite sides of the fulcrum.

8. In combination, a main and an auxiliary elastic fluid turbine, both being of the extraction type and being arranged to drive a common load, elastic fluid admission 70 valves for said turbines, a pressure regulator responsive to the extraction pressure of the auxiliary turbine operatively connected with the admission valve thereof, an elastic coupling means in said connection adjacent the regulator, a speed governor, a governor 75 lever therefor operatively connected with the pressure regulator, said connection including the elastic coupling means, an overflow valve for the main turbine, a pressure regulator responsive to the extraction pressure 80 of the main turbine, a lever connected therewith, a fulcrum for the lever connected with the governor lever, and means operatively connecting the overflow and admission valves of the main turbine with said lever in spaced relation to and on opposite sides of said fulcrum.

In witness whereof, I have hereunto set my hand this 19th day of October, 1923.

WALTER KIESER.
